UNITED STATES PATENT OFFICE.

WILLIAM P. HUFFMAN AND DANIEL L. FRY, OF HICKORY, NORTH CAROLINA.

FIRE-ESCAPE.

No. 899,984.

Specification of Letters Patent. Patented Sept. 29, 1908.

Application filed June 28, 1907. Serial No. 381,317.

To all whom it may concern:

Be it known that we, WILLIAM P. HUFFMAN and DANIEL L. FRY, citizens of the United States, residing at Hickory, in the 5 county of Catawba and State of North Carolina, have invented a new and useful Fire-Escape, of which the following is a specification.

This invention has relation to fire escapes 10 and it consists in the novel construction and arrangement of its parts as hereinafter shown and described.

The object of the invention is to provide a fire escape of simple and cheap construction 15 which may be easily and readily applied to and detached from the sill of a window frame or the mullion of a sash or other means of support and when so secured may be safely and quickly used as a means of descent from 20 a window or other elevated points.

The fire escape consists primarily of a cable having an engaging hook. A slideable handle piece is mounted upon the cable which is tortuously arranged through the same. The 25 said handle piece is provided in one end with an adjustable clamping mechanism which is adapted to regulate the frictional contact established between the handle piece and the cable. The handle piece is also provided 30 with a lever which may be forced laterally against the cable with more or less stretch thereby augmenting or diminishing the friction between the handle piece and the cable. The said lever is provided with a screw 35 mechanism which is adapted to engage the body of the handle piece, thereby, affording a mechanism means for positively holding the lever in contact with the cable. A depending stirrup is attached to the handle piece and 40 a thigh band is attached to said stirrup.

In the accompanying drawing:—Figure 1 is a perspective view of the fire escape. Fig. 2 is a sectional view of a portion of the same, and Fig. 3 is a side elevation of the upper portion of the handle piece with the ferrule in section.

The fire escape consists of the cable 1 to one end of which is attached a hook 2. Said hook is adapted to engage the edge of a window sill or the mullion of a sash or other fixed object, thereby, affording a means of attachment for the cable to a suitable support. The handle piece 3 is slideably mounted upon the cable 1. The upper end of said 50 handle piece is bifurcated as at 4 and the clamping jaws 5 are located in said bifurca-

tions. The lower ends of the jaws 5 are provided with the lugs 6 which fit in the recesses 7 whereby, longitudinal movement of the said jaws with relation to the handle piece 3 60 is prevented. The upper end of the handle piece 3 is exteriorly threaded as at 8 and the ferrule 9 engages said thread and passes around the jaws 5. The upper extremity of the ferrule 9 is reduced in interior transverse 65 dimension and consequently when the said reduced portion is moved toward the ends of the jaws the said jaws are forced into frictional contact with the cable 1. The handle piece 3 is provided with a longitudinal bore 70 10 and at intermediate points with the lateral bores 11 which enter the bore 10. The flanges 12 are located upon the outer side of the handle piece 3 and receive between them the bores 11. The cam lever 13 is fulcrumed between the flanges 12, and the cam 75 end of said lever engages the side of the cable 1. The screw 14 passes transversely through the lever 13 and is adapted to engage a threaded perforation provided in the 80 handle piece 3. The cable 1 passes through the end portions of the bore 10 and through the bores 11 and consequently have sections lying between the flanges 12 and directly against the side of the lever 13. The stirrup 85 15 depends from the handle piece 3 and is provided with a ring 16 to which is attached one end of a thigh band 17. The opposite end of the said thigh band is provided with a snap hook 18 which is adapted to engage the 90 ring 16.

From the foregoing description it will be seen that a fire escape with novel arrangement of parts is provided and that when in use the friction between the handle piece 95 and the cable may be augmented or diminished as desired by manipulating the ferrule 9 and the lever 13. In using the fire escape a person inserts one foot in the stirrup 15 and passes the band 17 around the opposite thigh and engages the hook 18 with the ring 16, thus, the handle piece is positioned within convenient reach and the said ferrule and lever may be manipulated during the course of a descent.

The fire escape is provided with a body band 19 which is provided at its ends with the snap hooks 20 adapted to engage the eyes 21 upon the handle piece 3. Said band is adapted to be passed around the body of one using the escape to make a descent. The body band is desirable at all times as is

also the thigh band 17 but the stirrup 15 may be dispensed with if desired. The specific arrangement of the bands and stirrup may be altered or changed in minor respects 5 without departing from the spirit of the invention.

Having described our invention what we claim as new and desire to secure by Letters-Patent is:—

10 A fire escape comprising a handle piece having a tortuous channel therethrough, a cable slidably located in said channel, a lever pivoted to the handle piece and adapted to engage the cable at the distorted portions of 15 said channel, clamping jaws mounted upon

the end of the handle piece at opposite sides of the cable and a ferrule screw threaded upon the end of the handle piece and surrounding the clamping jaws and adapted to force the jaws into frictional contact with 20 the said cable whereby the movement of the same therethrough may be governed.

In testimony that we claim the foregoing as our own, we have hereto affixed our signatures in the presence of two witnesses.

WILLIAM P. HUFFMAN.
DANIEL L. FRY.
